APPARATUS FOR REFINISHING TAMPICO ROLLS AND BRUSHES

Oscar A. Widerberg and Walfrid A. Wallsten,
Worcester, Mass., assignors to The American
Steel and Wire Company of New Jersey, a cor-
poration of New Jersey

Application July 31, 1946, Serial No. 687,304

13 Claims. (Cl. 51—84)

1

The present invention provides improved equipment for renewing the surfaces of rotary fabric brushes or rolls that are employed for buffing the surfaces on tempered and cold rolled strip steel. Such rolls rub the surfaces of the strip passing between them either for the removal of oil on the strip or, in the case of the so-called "tampico" rolls, rub the surfaces of the strip with a polishing compound, usually a mixture composed of about twenty-five per cent middlings and seventy-five per cent of hardwood sawdust, and supplied to the rolls at a predetermined rate from a hopper and distributing screw. Both rolls located after these tampico rolls, free the plate of substantially all of the oil with the middlings and sawdust adhering to the strip. The second part of the finishing train for the strip may consist of a stationary brush cleaning the plate supported by an underlying roll called a pipe roll, a pair of the so-called "tampico" rolls, and a pair of pipe rolls, these pipe rolls being formed from a pipe of proper diameter closed at both ends by welding and then wound with canton flannel. Besides their function in cleaning, these stiff rolls may be adjusted to exert a smoothing action on the surface when a bright finish is required. The tampico rolls usually are provided with fiber surfaces.

In view of the fact that these rolls act on oily surfaces that may have adhering polishing composition thereon, the rolls during service become saturated with oil and polishing composition, and become uneven in diameter, thus exerting unequal action on the strip surfaces, causing an imperfect polish thereon.

Consequently, it becomes desirable to renew the surfaces of such rolls by a suitable trimming operation to restore them to uniform diameter and increase their absorptive properties.

Various attempts to provide equipment including mechanical instrumentalities have been made, but the results obtained therewith were not completely satisfactory. Thus, in the investigation leading up to the present invention, there was tried a power-driven "lawn mower" type of trimmer, which was unsuccessful, as the polishing compound embedded in the brush dulled the trimmer blades too quickly. A rotary wire brush, running against the surface of the roll to be trimmed for loosening and displacing embedded polishing composition was tried in conjunction with the trimmer and gave better, but still unsatisfactory, service. A grinding wheel was substituted for the wire brush and a further improvement was noted. Finally the rotary trimmer was

2

discarded altogether and a combination of the wire brush and a grinding wheel revolving against the surface of the roll to be trimmed, was tried. This trimmer, which forms the subject matter of the present invention has given very good results in practice.

The invention will be understood more readily from the accompanying drawings, wherein:

Figure 1 is an end elevation of a trimming machine adapted to trim the surface of fabric, cord, or tampico rolls which have been worn in service, for the purpose of restoring such rolls to a uniform diameter;

Figure 2 is a top plan view of the apparatus, parts being omitted for clarity;

Figure 3 is a side elevation of the apparatus of Figures 1 and 2;

Figure 4 is a sectional elevation of the apparatus, the view being taken on the line IV—IV of Figure 3;

Figure 5 is a fragmentary enlarged sectional plan view of a bearing for one end of the reciprocating shaft upon which the brush or roll to be refinished is mounted, the view being taken along the line V—V of Figure 3, looking in the direction of the arrows, the view also showing means permitting removal of the reciprocating shaft for mounting and demounting the tampico roll to be refinished; and

Figure 6 is a fragmentary sectional plan view of adjusting instrumentalities for effecting adjustment of the refinishing tools relative to the tampico roll being refinished.

Referring more particularly to the drawings, the mechanism of the present invention is shown as being mounted on a frame or base A on each end of which is mounted a longitudinally sliding platform, one of which is indicated at B and the other is indicated at C. A laterally extending bracket D also is provided, which is suitably secured to the base A preferably midway between the ends.

As is shown on the drawings, reference being made first to Figures 1, 2, and 3, the platform slide B is extended upwardly at its inner end into a pair of spaced upstanding brackets 8, 8a, which carry bearings 10, 10a for shafts 12, on each of which is mounted a power-driven working tool 14 or 150. For rotating the tools 14, 150, there are provided motors 16 and mounting instrumentalities for the motor. Each of these mounting instrumentalities for the motors 16 comprises spaced base studs 18, 18a that are bolted, or otherwise secured by bolts or other suitable fastening devices indicated at 20 to the

platform slides B and C. A plate 22, provided with laterally extending trunnions 24, 24a that are received in bearings 26, 26a on the base studs 18, 18a, forms a mounting for each of the motors 16. Lever arm 28, integral with the mounting plate 22 and provided with a pin 30 that is received in an arcuate slot 32 in a bracket angle plate 34, which plate is secured to the slide platform in a suitable manner to give rigidity of mounting such as by a bolt or the like 36, provides a means for effecting any necessary adjustment of the motors 16 relative to the tools 14 or 150, suitable clamping means, such as nut 38 being provided for securing the proper adjustment of the tool shaft 12. The tool shaft 12 is provided at one end with a sheave 35, which in practice receives V-belt 37 that pass over the sheave 35 and the driving sheave 40 on motor shaft 42.

The slide platform B as well as the platform C is mounted for sliding movement on a slide track 44, see Figure 4, which forms a sliding mounting for the platform, the lateral plate-like extensions of which, indicated at 46, form attaching means for the base A and housing 48 for adjusting instrumentalities, as will be pointed out in more detail hereinafter, attachment being afforded by means of bolts 50 and machine screws 52. The slide surfaces of the slide platform are protected by wear plates 54 secured by screws 56 or the like.

The working tool 14 may be, in this instance, a wire brush adapted to operate on the surface of the tampico roll or brush, indicated by reference numeral 60, which is to be refinished. This tampico roll or brush is adapted to be received on a shaft 62 that is adapted to be reciprocated with a short stroke, in practice about three-eighths of an inch, by suitable mechanism in a reciprocation head 64 that is mounted on laterally extending bracket D. This reciprocating shaft 62 is mounted in suitable bearings which permit reciprocation, one of which bearings is shown in section in Figure 5, and which will be referred to in detail hereinafter. At this point, it may be noted that the shaft 62 is driven by a V-belt sheave 66 that is mounted adjacent to an end of the shaft 62, V-belt 68 passing over the sheave 66 and over a corresponding V-belt drive sheave 70 on one end of motor shaft 72 of the driving motor 74.

For reciprocating the shaft 62, it is provided with a driven end sheave 76 that engages with V-belt 78, which engage a driven V-belt sheave 80 on a worm shaft 82 that extends into the reciprocation head or housing 64, in which are provided bearings 84 for the worm shaft 82. This worm shaft 82 carries a worm 86 that meshes with a worm gear 88 on shaft 90. This shaft 90, which extends substantially at right angles to shaft 82, carries a cam 92, on which cam is an eccentric follower indicated at 93, that terminates in an extension 95 to which is connected one arm of a bell crank shift lever 94, the other arm of which is formed into a yoke that straddles the shaft 62 between collars 98 and 99 that are rigidly mounted on the shaft 62 so that they are, in effect, integral with the shaft, the bell crank yoke 96 being provided with inwardly projecting pins 100, 101, that stop short of the shaft 62, but engage the collars 98 and 99 alternately as the shift yoke 96 reciprocates responsive to movement of the eccentric follower 93 that raises and lowers its connected arm of the bell crank shift lever 94. The shift lever 94 is fulcrumed on pin 102 that is mounted in the housing 64.

It will be seen from the drawings, Figure 3,

that the shaft 62 is mounted in bearings that permit both rotation and reciprocation of the shaft, this reciprocation being effected by engagement of the pins 100, 101 with first one of the collars 98 and 99, and then with the other. The construction of one of these bearings, which permits this reciprocation and rotation, while also permitting assembling and disassembling of the shaft assembly for mounting and demounting the tampico rolls on the shaft 62, is shown in Figure 5, which view also illustrates means for clamping the shaft assembly against reciprocation whenever such may be desired.

The shaft assembly referred to comprises a stand which carries an end bearing 104, the bearing stand being indicated at 106. This bearing stand comprises a pair of spaced, yieldable legs to be referred to hereinafter in greater detail, that are mounted on a slide 108 extending transversely across the top of the base of the machine. Other suitable bearings, not shown in detail, form additional supports for the shaft 62, while permitting oscillation of the shaft through such bearings.

The construction of the end bearing 104 is shown in detail in Figure 5.

This construction, as shown in detail in Figure 5, indicates that the end bearing is composed of anti-friction bearing elements 110 that are retained in a bearing roll, the outer member of which is a tubular insert 112 fitted into the bracket 106, the inner member of the bearing roll being a sleeve 114 that encloses a restricted end portion 116 of the shaft, and abuts against shoulder 118 between the restricted portion 116 of the shaft and the remainder thereof. The bearing roll is closed by closures 120, 122, which are adapted to retain lubricating packing or the like 124, 126, the closures 120, 122 being secured to the bracket 106 by screws 125 so that they may be removed. A collar 128 mounted on the shaft 62 and held in place by a removable screw 130 serves as a stop for the tampico roll or brush 60 which is being refinished. The outer end of the sleeve 114 abuts against a collar 132 at the outer end of the restricted portion 116 of the shaft 62 and is secured to the shaft portion 116 by a removable screw 134. Collars 128 and 132 form stops for limiting reciprocation of the shaft to the desired length of stroke. Removal of the collar 132 enables the bearing and bracket assembly to be slipped off from the slide 108 to permit release of the screw 130 from the collar 128 and screw 134 from the collar 132, so that the collar 132 may be removed to enable the bearing and bracket assembly to be removed from the shaft, thereby enabling the shaft and the now-refinished roll or brush 60 to be demounted, removal of the collar 128 permitting the tampico brush or roll 60 to be removed. Replacement thereof, with another such roll or brush to be refinished is accomplished by a reverse of these operations for reassembling the shaft and bearing.

It will be understood that except when it is desired to demount the shaft and brush or roll after refinishing, the bracket 106 is clamped rigidly to the slide 108. For this purpose, a lever 140 is mounted on a threaded shaft 142 that extends through both spaced legs 144 of the bracket 106 straddling the slide 108, and a stop 146 is positioned between these leg portions 144. Turning the lever 140 in a counter-clockwise direction as shown, clamps the leg portions 144 of the bracket or bearing stand 106 against the sides of the

slide 108. The stop 146 between the leg portions 144 prevents possibility of compressing the leg portions beyond their elastic limit. In practice, the stop 146 may be provided with a suitable hole for the passage of the shaft 142, and this shaft may be threaded only along a portion thereof adjacent to its outer end, as indicated at 148. When the brush or roll 60 is to be removed after refinishing, the lever 148 is turned in a clockwise direction to release the leg portions 144 from the slide track 108, and enable the removal of the bearing from the shaft after the collar 132 has been removed from the shaft portion 116.

There now remains to be described the adjustment of the slide platforms B and C with their working tools that are carried thereon. As has been pointed out above, tool 14 is a wire brush that is adapted to act on the fabric surface of the tampico roll or brush 60 to scarify and loosen the surface of the fabric that is impregnated with polishing composition and other foreign material. The loosened nap then is ground off, together with its associated foreign materials, by means of the tool 150, which may be a grinding wheel, or the like. In view of the fact that the roll or brush 60 that is being refinished has to be evenly surfaced concentrically with its axis and shaft 62, it is necessary that the slides B and C be adapted to be moved equally towards the roll or brush 60 for even application of the finishing tools 14 and 150 against the roll 60.

It will be understood that the slide platforms B and C are duplicated in their construction and mounting, so that the detailed description given above for the mounting of the refinishing tool 14 and motor 16 and the drive connection between the tool shaft 12 and the motor 16 applied equally to the mounting and operation of the slide platform C; and the slide mounting of the platform C, being similar to that of the platform B, the repetition of all of such detailed description becomes unnecessary.

Passing now to the adjustment means for actuating the platforms B and C, there are provided, first, an independent, rapid manual adjustment of the tools to the surface of the tampico roll or brush to be refinished, and, second, simultaneous manual adjustment of the tools against the roll being refinished, these manual adjustments providing means for equally applying the tools 14 and 150 to the tampico roll being refinishing.

In order to effect such adjustments, each slide platform B and C is mounted on a threaded shaft 152, each of which extends through opposite end aprons 154 and 156 of the slide platforms B and C, and turns in gear 158 that is mounted on the shaft 152 through turning a handwheel 160 that is mounted as shown on the end of the shaft 152. Each handwheel 160 carries a retractable locking pin 162, an end of which is adapted to enter a hole in the outer end apron 154 by pressure of a spring 164, a knurled head 166 on the head of the pin enabling it to be pulled readily out of engagement with the hole. Retraction of the pin 162 releases handwheel 160 for rotation manually by handle 168, the handwheel being tightly mounted on the shaft 152. Rotation of the handwheel 160 turns the shaft 152, which moves through stationary gear 158 to apply each of the tools to the tampico rolls or retract them therefrom, as desired, depending on the direction of rotation of the handwheels 160 and shafts 152. Each of these threaded shafts 152 is held by thrust bearings 170, 172. Cap screws 176 hold

the housing walls secured to the frame A. A bottom plate 178 is held in place by cap screws 180 and bolts 181, this plate extending continuously from one gear housing 48 to the other gear housing, as shown, forming the mounting means for the gear housing and for shaft bearings 182, for holding the shafts 184.

Each of the shafts 184 projects through each of the gear housings 48 through bearings 185 in end walls 174, and is provided with an end nut 186. On the portion of each shaft in the respective gear housing 48 is a driving pinion 188, which engages each of the gears 158, for effecting simultaneous and equal adjustment of the carriage platforms B and C and the tools 14 and 150 relative to the tampico roll or brush 60.

Each of the shafts 184 is provided at its inner end with a bevel gear 190. These bevel gears 190 engage a driving bevel gear 192 on the end of shaft 194, which has an enlarged sleeve 196, turnable integrally with the shaft and which carries a gear 198 and a manual handwheel 200 provided with an operating handle 202. This handwheel provides a simultaneous adjusting means for the tools 14 and 150, through shaft 194 and the shafts 184 driven through shaft 194 and the above-described bevel gear connections. Manual operation of the handwheel 200 effects a rapid adjustment of the tools, simultaneously and equally, relative to the brush or roll 60 which is to be refinished.

In order to effect such simultaneous adjustment, locking pins 162 of handwheels 160 must be entered into their respective locking engagement with the carriages B and C so as to lock these handwheels against rotation while the shafts 152 are turned by the driving action of the pinions 188, on the shafts 184. Gears 158 then act as nuts to drive the shafts 152.

As the resurfacing or refinishing of the tampico brush or rolls is effected after manual application of the working tools 14 and 150 against the brush or roll 60, it becomes necessary to produce an equal but gradual feed-in of the tools as the old surface of the brush or rolls 60 proceeds. This requisite "fine" adjustment is effected by power driven instrumentalities which now will be described.

Gear 198 is adapted to mesh with a pinion 204 on a sleeve 206 movable integrally with stub shaft 208 suitably off-set from shaft 194 and sleeve 196. The stub shaft 208 carries at its outer end a ratchet wheel 210, provided with a requisite number of teeth to provide the requisite very fine feed-in for the tools 14 and 150 when these tools are operating on the brush or roll 60. On the shaft 208 and operably connected with the ratchet wheel 210, is a bell crank 212, one arm of which, designated 214, carries a pawl 216 pivotally mounted to the bell crank arm 214 as indicated at 218, this pawl engaging the teeth of the ratchet wheel 210 by a positive engagement through action of a spring 220.

The other arm of bell crank 212 designated at 222 is pivotally connected at 224 to a pitman 226 carried on an eccentric 228 on shaft 230. Shaft 230, like shafts 194 and 208, projects through the frame A of the machine, and the pitman 226, eccentric 228, ratchet wheel 210, bell crank 212 and handwheel 200 being on the outside of this frame A for accessibility. The shaft 230 passes through bearings 232 and 234 in the frame A of the machine and is shown as being connected at 236 with the driving shaft 238 of a speed reducer 240 driven by motor 242. Therefore, operation

of motor 242 drives the shaft 230 at requisite speed to turn the eccentric 228, thereby lifting and lowering the pitman 226 to actuate pawl 216, which engages a predetermined number of teeth in the ratchet wheel 210, for turning the ratchet wheel 210 through a corresponding arc, the length of which arc is adjustable, depending upon the angularity of the bell crank 212 with respect to the pitman 226, the greater this angularity, the larger the number of ratchet teeth between each operative engagement of the pawl 216 therewith. This adjustment may be effected by an arcuate, apertured bar 244 concentric with the stub shaft 208, and connected to the bell crank 212 by a pin 246 on the end of arm 248 which connects with the bell crank 212 to change the angularity of the bell crank 212 with the pitman 226 as may be desired, depending upon the hole 250 in the apertured bar 244 in which the pin 246 is received. A second pawl 252 is provided for locking the ratchet wheel 210 in its adjustment, so as to assure the desired movement of this ratchet wheel.

Each actuation of the pitman in an upward direction moves the arm 214 of bell crank 212 in a counter-clockwise direction as viewed in Figure 3, the locking pawl 252 holding the ratchet wheel 210 against movement as the actuating pawl 216 rides over the teeth of the ratchet wheel for the predetermined adjusted distance. The downward stroke of the pitman engages the pawl 216 with the ratchet wheel teeth, thereby moving the ratchet wheel through the prescribed distances. This movement of the ratchet wheel is transmitted through the gear and shaft trains to turn shafts 152 correspondingly thereby feeding the tools 14 and 150 equally against the surface of the tampico brush or roll 60 which also may be reciprocating as well as revolving so that all parts of the surface thereof are brought into engagement with these tools. This also causes corresponding movement of the handwheel 200, but this is unsequential.

Locking pawl 252 is pivotally mounted on frame A as is indicated at 254; and as has been said above, pawl 216 is pivotally mounted at 218 on the crank arm 214. Therefore, a manual lifting of these pawls breaks the driving connection between the ratchet wheel 210 and pitman 226, thence to shaft 230 and motor 242, thereby enabling manual operation of the handwheel 200 to be permitted, with corresponding rapid retraction of the tools 14 and 150 from the now resurfaced brush or roll 60, which then may be demounted as described above and replaced with another brush or roll to be resurfaced.

If desired, a guard 256 may be provided as shown to protect an operator around flying fragments from the roll 60.

It will be understood that when independent manual adjustment of the tools 14 and 150 is to be desired, shafts 152 turn through the gears 158 and move relatively through the gears, these gears 158 being held against rotation by the friction between the gears 158 and pinions 188, between the shafts 184 with bevel gears 190 thereon and bevel gear 192 on shaft 194, between gear 198 on shaft 194 and pinion 204 on shaft 208, between the pawls 252 and 216 and ratchet wheel 210 on the shaft 208, and between the bell crank 212; pitman 226 and motor shaft 230; but when the handwheels 160 are locked by pins 162 against turning, and power is applied to the gears 158 either by turning the handwheel 200 or through driving from motor 242, the gears 158 act as nuts

on the shafts 152, to feed these shafts and carriages B and C towards or away from the work, depending on the direction of rotation of these gears 158.

- 5 As the tools 14 and 150 act on the roll 60, that is being refinished, the wire brush 14 pulls up the nap of the fabric and loosens the impregnated portion of the fabric of the roll, so that it can be removed effectively by the grinding wheel 160.
- 10 Reciprocation of the roll 60 during this operation assures contact of all portions of the roll surface with the working tools, it being understood, of course, that the roll 60 is being also rotated during the refinishing operation. Upon completion of the resurfacing, the roll has been provided with a feed surface that is concentric with the axis of the roll.

While the foregoing detailed description and the accompanying drawings shown are exemplary embodiments of the invention in an illustrative manner, it will be understood that the invention is not limited necessarily to the particular details herein specifically illustrated and described, it being understood that such may be modified within the skill of one skilled in the art without departing from the inventive concept as may be necessary to adapt the invention to varying conditions as uses, as defined by the appended claims; and while the invention is illustrated and described in connection with the resurfacing of tampico rolls or brushes, it will be understood that it is of general application in so far as concerns the feeding mechanisms for the working tool carriages and the reciprocation of the work during rotation thereof for even application of the tools to all portions of the surface of the work.

We claim:

1. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, mechanism for simultaneously adjusting the said working tools toward the workpiece, means for effecting a predetermined progressive simultaneous engagement of the working tools with the workpiece for predeterminedly acting upon the workpiece for imparting the predetermined surface to the workpiece, means for rotating the workpiece during engagement of the tools therewith, and mechanism for linearly oscillating the workpiece during rotation thereof for presenting all surfaces thereof to the said tools.
- 40 2. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, mechanism for simultaneously adjusting the said working tools toward the workpiece, means for effecting a predetermined progressive simultaneous engagement of the working tools with the workpiece for predeterminedly acting upon the workpiece for imparting the predetermined surface to the workpiece, means for rotating the workpiece during engagement of the tools therewith, and mechanism for linearly oscillating the workpiece during rotation thereof for presenting all surfaces thereof to the said tools.
- 50 3. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, mechanism for simultaneously adjusting the said working tools toward the workpiece, means for effecting a predetermined progressive simultaneous engagement of the working tools with the workpiece for predeterminedly acting upon the workpiece for imparting the predetermined surface to the workpiece, means for rotating the workpiece during engagement of the tools therewith, and mechanism for linearly oscillating the workpiece during rotation thereof for presenting all surfaces thereof to the said tools.
- 60 4. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, manually operated mechanism for independently adjusting each of the working tools relative to the workpiece, manually operated mechanism for effecting equal and simultaneous adjustment of the working tools toward the workpiece, power-driven means for simultaneously rotating the working tools, power-actuated mechanism for effecting a predetermined progressive simultaneous engagement of the working tools with the workpiece for imparting the predetermined surface to the workpiece, and mechanism for ro-
- 70 5. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, manually operated mechanism for independently adjusting each of the working tools relative to the workpiece, manually operated mechanism for effecting equal and simultaneous adjustment of the working tools toward the workpiece, power-driven means for simultaneously rotating the working tools, power-actuated mechanism for effecting a predetermined progressive simultaneous engagement of the working tools with the workpiece for imparting the predetermined surface to the workpiece, and mechanism for ro-
- 75 6. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools carried by the mounting frame, means for adjusting each of the working tools independently of the other relative to the workpiece, manually operated mechanism for independently adjusting each of the working tools relative to the workpiece, manually operated mechanism for effecting equal and simultaneous adjustment of the working tools toward the workpiece, power-driven means for simultaneously rotating the working tools, power-actuated mechanism for effecting a predetermined progressive simultaneous engagement of the working tools with the workpiece for imparting the predetermined surface to the workpiece, and mechanism for ro-

9.

tating the workpiece as the working tools act upon it for peripherally presenting all portions of the surface of the workpiece to the working tools.

3. Mechanism for producing a predetermined surface on a cylindrical workpiece, which comprises, in combination, a mounting frame, means on the frame for receiving the workpiece, a pair of oppositely disposed working tools one on each side of the workpiece, adjustable carriage means for the working tools mounted on the said frame, manually operated mechanism for independently adjusting each of the carriages and the working tools mounted thereon relative to the workpiece, manually operable mechanisms for effecting equal and simultaneous adjustment for the working tools toward the workpiece, power-actuated mechanism for effecting a predetermined progressive simultaneous engagement of the working tools with the workpiece for imparting the predetermined surface to the workpiece, power mechanism for rotating the workpiece as the working tools act upon it for circumferentially presenting the workpiece to the tools, and instrumentalities operated by the said power mechanism for linearly oscillating the workpiece during rotation thereof for presenting all portions of the surface of the workpiece to the working tools.

4. Mechanism for producing a predetermined surface on a cylindrical workpiece, which comprises, in combination, a mounting frame, a slide track on the mounting frame extending transversely thereof, a rotatable shaft having an inner end and an outer end, said shaft being adapted to support a workpiece for movement therewith, bearing means for the shaft positioned adjacent to the outer end of the shaft, a bracket bearing stand assembly for the bearing having spaced leg portions straddling the slide track, means for releasably clamping the said leg portions against the slide track, the said bearing means permitting reciprocation of the shaft and workpiece, mechanism for rotating the shaft and workpiece, instrumentalities driven by the said mechanism for oscillating the shaft and workpiece during rotation thereof, working means for surfacing the workpiece, and mechanism for adjusting the working means relative to the workpiece.

5. Mechanism for producing a predetermined surface on a cylindrical workpiece, which comprises, in combination, a mounting frame, a slide track on the mounting frame extending transversely thereof, a rotatable shaft having an inner end and an outer end, said shaft being adapted to support a workpiece for movement therewith, bearing means for the shaft positioned adjacent to the outer end of the shaft, a bracket bearing stand assembly for the bearing having spaced leg portions straddling the slide track, means for releasably clamping the said leg portion against the slide track, the said bearing means permitting reciprocation of the shaft and workpiece, mechanism for rotating the shaft and workpiece, instrumentalities adjacent to the inner end of the shaft driven by the said mechanism for oscillating the shaft and workpiece during rotation thereof, means on the shaft cooperating with the bearing means for limiting amount of reciprocation of the shaft, means permitting demounting of the bearing means and bracket bearing stand assembly from the shaft and slide track, thereby enabling removal of the shaft and workpiece after surfacing operations on the workpiece, surfacing means for surfacing the workpiece, and mechanism on the mounting frame for adjusting the surfacing

10

means relative to the workpiece during rotation and reciprocation of the shaft and workpiece.

6. Mechanism for producing a predetermined surface on a cylindrical workpiece, which comprises, in combination, a mounting frame, a slide track on the mounting frame extending transversely thereof, a rotatable shaft having an inner end and an outer end, said shaft being adapted to support a workpiece for movement therewith, bearing means for the shaft positioned adjacent to the outer end of the shaft, a bracket bearing stand assembly for the bearing having spaced leg portions straddling the slide track, means for releasably clamping the said leg portions against the slide track, the said bearing means permitting reciprocation of the shaft and workpiece, mechanism for rotating the shaft and workpiece, instrumentalities adjacent to the inner end of the shaft driven by the said mechanism for oscillating the shaft and workpiece during rotation thereof, removable collars on the shaft cooperating with the bearing means for acting as stops for limiting amount of reciprocation of the shaft, removal of the said collars and release of the clamping means permitting demounting of the bracket bearing stand and removal of the shaft and workpiece, tool means for working on the workpiece, and means on the mounting frame for adjusting the tool means relative to the workpiece during rotation and oscillation thereof for surfacing the said workpiece.

7. Mechanism for producing a predetermined surface on a cylindrical workpiece, which comprises, in combination, a mounting frame, mechanism for mounting the workpiece on the mounting frame for surfacing operations, instrumentalities for imparting rotary and reciprocatory motions to the workpiece, working tools adapted to work on the workpiece for producing the predetermined surface thereon, independent driving means for the tools, means for effecting manual rapid independent adjustment of the tools relative to the workpiece, means for effecting manual rapid simultaneous adjustment of the tools toward the workpiece, and power-actuated mechanism for effecting a predetermined fine and equal adjustment of the tools against the workpiece.

8. Mechanism for refinishing fabric polishing rolls, which comprises, in combination, mounting instrumentalities for a roll to be refinishing, drive mechanism for rotating the roll, a pair of oppositely disposed working tools adapted to engage the roll, one of the said tools being a wire brush adapted to loosen surface fabric from the roll, and the other tool being a grinding wheel adapted to remove the loosened fabric and to smooth the remaining fabric on the roll, independent driving means for rotating the tools, means for effecting rapid manual and independent adjustment of the tools relative to the workpiece, mechanism for effecting rapid manual and simultaneous adjustment of the tools relative to the workpiece, and power-actuated mechanism for effecting a predetermined fine and equal adjustment of the tools against the workpiece.

9. Mechanism for refinishing fabric polishing rolls, which comprises, in combination, mounting instrumentalities for a roll to be refinishing, drive mechanism for rotating the roll, a pair of oppositely disposed working tools adapted to engage the roll, an adjustable carriage for each of the tools, driving means for each tool mounted on each carriage, manually actuated adjustment means for each carriage for independently adjusting each of the tools, manually actuated ad-

11

justment means for simultaneously and equally adjusting the tools relative to the workpiece, power-actuated mechanism for effecting progressive and equal step-by-step feed of the tools against the workpiece, and means for adjusting the magnitude of such movement.

10. Mechanism for refinishing fabric polishing rolls, which comprises, in combination, a mounting frame, mounting instrumentalities for a roll to be refinished and carried by the mounting frame, drive mechanism for rotating the roll, a pair of oppositely directed working tools adapted to engage the roll diametrically oppositely, one of the said tools being a wire brush adapted to penetrate and tear loose surface layers of fabric on the roll, the other tool being a grinding wheel adapted to grind off the thus-loosened fabric layers, and to smooth remaining fabric layers on the roll, a carriage for each of the tools slidably mounted on the frame, driving means for each tool mounted on each carriage, an apron depending from each end of each carriage, a threaded shaft extending through the aprons of each carriage, bearings in the mounting frame for each threaded shaft, a handwheel on each threaded shaft for effecting independent manual adjustment of the carriages and tools thereon relative to the roll, a drive gear on each threaded shaft, a pair of aligned driving shafts having adjacent ends and remote ends, a driving pinion on the remote ends engaging with the gear on each threaded shaft, a bevel pinion on the adjacent ends of the driving shafts, an operating shaft for the driving shafts, a bevel gear on the operating shaft adapted to engage the bevel pinions on the driving shafts, a handwheel on the operating shaft for manually effecting simultaneous and equal actuation of the driving shafts and driving pinions, thereby producing simultaneous and equal adjustment of the carriages and tools, a gear on the operating shaft, a ratchet shaft, a pinion on the ratchet shaft in mesh with the said gear on the operating shaft, a ratchet wheel on the ratchet shaft, cooperating pivotally mounted pawls for the ratchet wheel, a bell crank on the ratchet shaft, one arm of which carries one of the pawls, a pitman pivotally connected to the other arm of the bell crank, a motor shaft passing through the mounting frame and having bearings therefor in the mounting frame, an eccentric on the motor shaft, means connecting the pitman to the eccentric on the motor shaft, a motor for driving the motor shaft, and means for angularly adjusting the bell crank on the ratchet wheel for predeterminedly varying the arc of contact between the pawl on the bell crank and the ratchet wheel, thereby adjusting the amount of throw of the ratchet wheel for each stroke of the pitman for predeterminedly controlling amount of travel of the carriages and tools against the roll being refinished.

11. Mechanism for refinishing fabric polishing rolls of the class identified as tampico rolls, which comprises, in combination, a mounting frame, mounting instrumentalities for a roll to be refinished carried by the mounting frame, drive mechanism for rotating the roll, a pair of oppositely directed working tools adapted to engage the roll diametrically oppositely, one of the said tools being a wire brush adapted to penetrate and to tear loose surface layers of fabric on the roll, the other tool being a grinding wheel adapted to grind off the thus-loosened fabric layers, and to smooth the remaining fabric layers on the roll, a carriage for each of the tools slidably mounted on the frame, driving means for each tool mounted on each carriage, an apron depending from each end of each carriage, a threaded shaft extending through the aprons of each carriage, bearings in the mounting frame for each threaded shaft, a handwheel on each threaded shaft for effecting independent manual adjustment of the carriages and tools thereon relative to the roll, a drive gear on each threaded shaft, a pair of aligned driving

12

shafts mounted in the mounting frame having adjacent ends and remote ends, a driving pinion on the remote ends engaging with the gear on the said threaded shafts of the carriage shafts, a bevel gear on the adjacent ends of the driving shaft, an operating shaft for the driving shafts, the operating shaft being mounted in the mounting frame, a bevel gear on the operating shaft adapted to engage the bevel pinions on the driving shafts, a handwheel on the operating shaft for manually effecting simultaneous and equal actuation of the driving shafts and driving pinions, thereby producing simultaneous and equal adjustment of the carriages and tools, a gear on the operating shaft, a ratchet shaft, a pinion on the ratchet shaft in mesh with the said gear on the operating shaft, a ratchet wheel on the ratchet shaft, cooperating pivotally mounted pawls for the ratchet wheel, a bell crank on the ratchet shaft, one arm of which carries one of the pawls, a pitman pivotally connected to the other arm of the bell crank, a motor shaft passing through the mounting frame and having bearings therefor in the mounting frame, an eccentric on the motor shaft, means connecting the pitman to the eccentric on the motor shaft, a motor for driving the motor shaft, and means for angularly adjusting the bell crank on the ratchet wheel for predeterminedly varying the arc of contact between the pawl on the bell crank and the ratchet wheel, thereby adjusting the amount of throw of the ratchet wheel for each stroke of the pitman for predeterminedly controlling amount of travel of the carriages and tools against the roll being refinished.

12. The method of refinishing a fabric polishing roll which comprises rotating said roll, feeding a rotating wire brush against said roll to tear loose surface layers of fabric thereon, and feeding a rotating grinding wheel against said roll to grind off the loosened fabric layers and to smooth remaining fabric layers on the roll.

13. The method of refinishing a fabric polishing roll which comprises rotating said roll, feeding a rotating wire brush against said roll from one side thereof to tear loose surface layers of fabric thereon, and simultaneously feeding a rotating grinding wheel against the opposite side of said roll to grind off the loosened fabric layers and to smooth remaining fabric layers on the roll.
